CONTAINER

John M. Hothersall, Brooklyn, N. Y., assignor to
 American Can Company, New York, N. Y., a
 corporation of New Jersey

Application April 11, 1935, Serial No. 15,872

4 Claims. (Cl. 221—64)

The present invention relates to powder or the like dispensing containers and has particular reference to a top construction having cooperatively arranged eccentric devices for opening and closing the dispensing opening or openings.

An object of the invention is the provision of an improved top construction for a powder or the like dispensing container wherein rotation of an outer top part causes actuation of eccentrically disposed means for opening and closing a dispensing aperture or apertures in an inner top part through which the contents of the container are dispensed.

Another object is the provision of such a dispenser top construction wherein sifter or pouring perforations in a top part may be selectively brought into or out of registration with corresponding dispensing perforations in another top part for dispensing the container contents or for closing the container.

Another object is the provision of such a dispenser top construction which provides a tight and smooth sealing contact between the various parts without outwardly protruding parts, thereby sealing the container against accidental escape of contents, especially when finely powdered products are to be packed therein, while at the same time permitting easy and smooth opening and closing.

Numerous other objects and advantages of the invention will be apparent as it is better understood from the following description, which, taken in connection with the accompanying drawing, discloses a preferred embodiment thereof.

Referring to the drawing:

Fig. 1 is a perspective view of a container having a dispenser top construction embodying the instant invention;

Fig. 2 is an enlarged fragmentary top plan view of the dispenser top illustrated in Fig. 1 showing the dispensing perforations closed or out of registry, parts of the top being broken away;

Fig. 3 is a view similar to Fig. 2 showing the dispensing perforations open or in registry for a dispensing operation; and

Fig. 4 is a vertical cross sectional view of the upper part of the container and the dispenser top as taken substantially along the line 4—4 in Fig. 3.

A preferred form of the invention which is illustrated in the drawing comprises a container having a cylindrical body 11, closed at its bottom by a bottom end 12 secured to the body in any suitable manner. At its upper end the body is closed by a cover or breast 13 having a depending

annular flange or wall 14 which frictionally engages or slips over a reduced or necked in wall part 15 formed in the upper end of the body. The breast 13 above the flange 14 extends inwardly and upwardly to provide a tapered wall part 13a, 5 a curved wall part or channel 18 and a vertical wall part 19. This latter wall section merges into a substantially flat horizontal top 21 which constitutes the stationary or fixed member of the dispenser top construction. It will be readily 10 seen that instead of having a separate cover or breast the body 11 may be directly provided with a top wall like wall 21.

A movable member or closure of the dispenser top construction is carried in a circular recess or 15 depression or pocket 26 of the top 21 and comprises a disc 25 (Figs. 2, 3 and 4) having its bottom surface 27 lined with a gasket 28 of any suitable material which makes tight sealing contact with the bottom of the recess while the upper surface of the disc is flush with the upper surface of the top 21. The disc is rotatable in the pocket 26 and is provided for this purpose with a centrally disposed depending projection or pivot 29 which pivots in an indentation 31 20 25 formed in the recess wall of the top 21.

The recess or pocket 26 and the disc 25 carried therein are eccentrically disposed relative to the top 21 and the geometrical center of the top is caused to be positioned within the boundary of the recess. About this center a dispensing 30 perforation or opening 32 is formed in the recess 26 and is normally covered by the disc 25.

For uncovering the dispensing opening 32 so as to dispense the container contents, the disc 35 25 is in the preferred illustration herein provided with a circularly arranged group of sifting perforations 33 and a single circular pouring perforation 34 which may be selectively brought into registration or aligned with the perforation or 40 dispensing opening 32 of the top recess 26 by rotating the disc about its pivot 29.

Rotation of the disc 25 is effected by a second movable member or closure in the top construction which comprises an outer rotatable cup 45 shaped outer closure 36 having a flat top wall section 37, which in part engages the upper surface of the stationary top 21. The cover is formed with a depending flange or wall section 38 which is parallel with and rotatably hugs the 50 vertical wall section 19 of the breast 13. The bottom marginal part of this flange is bent under the bottom of the wall section 19 and into engagement with a portion of the curved wall section 18 for holding the outer closure in place so that 55

it can be rotated concentrically around the top 21. This outer closure 36 is also provided with a central circular dispensing opening 39, which is in permanent alignment with the circular opening 32. The outer closure 36 also holds the disc 25 in the pocket 26 intermediate the outer closure and the inner top 21.

Rotation of the disc 25 by the closure member 36 is effected by a depending finger, tongue or lug 41 which is struck out from the top wall section 37 of the closure. The lug 41 depends through a radial slot 42 formed in the disc 25 (Figs. 3 and 4) and terminates in an arcuate clearance groove 43 formed in the bottom wall 15 of the pocket 26. When the outer closure member 36 is rotated on the stationary top 21 the side of the slot serves as a cam for the engagement of the lug 41 to revolve the disc 25 on its axis 29 within the confining pocket 26, said axis 20 being eccentric to the common longitudinal axis of the container and rotatable actuating closure member 36.

The position of the radial slot 42 in the disc is preferably directly opposite the sifter perforations 33 so that when the lug 41 is intermediate the extremes of its travel the perforations 33 are in alignment with the dispensing openings 32 and 39, as shown in Fig. 3. When the outer closure 36 is turned clockwise from the position shown in Fig. 3 the disc alines the pouring opening 34 with the dispensing openings 32 and 39, the outer end of the slot 42 acting as a stop against which the lug engages for properly aligning the perforations. Similarly, when the closure 35 36 is turned counter-clockwise to the position shown in Fig. 2 communication between the openings 32 and 39 is entirely cut off by the unperforated part of the disc 25. The movement of the disc and closure in this direction is also properly limited by engagement of the lug 41 with the outer end of the slot 42.

It is thought that the invention and many of its attendant advantages will be understood from the foregoing description, and it will be apparent 45 that various changes may be made in the form, construction and arrangement of the parts without departing from the spirit and scope of the invention or sacrificing all of its material advantages, the form hereinbefore described being 50 merely a preferred embodiment thereof.

I claim:

1. A dispensing top for a container having in combination, a stationary top adapted to be attached to a container and having a depressed circular pocket, a dispensing opening formed in and eccentric to said pocket, a disc seated in said pocket and rotatable therein and having sifting openings and a closing portion and a slot extending radially toward the periphery of said disc, and an outer closure rotatably mounted on said top and formed with a dispensing opening in line with the path of said sifting openings and closing portion of said disc and having a

depending finger engaging the slot of the disc, the outer end of said radial slot constituting means for limiting the rotary movement imparted by said outer closure through said finger to said disk in both directions to open and close said dispensing opening. 5

2. A dispensing top for a container having in combination, a stationary top adapted to be attached to a container and having a depressed circular pocket, a dispensing opening formed in and eccentric to said pocket, a disc seated in and pivotally connected with the bottom of said pocket and rotatable therein and having sifting openings and a closing portion and a radially disposed slot extending toward the periphery of said disc, and an outer closure rotatably mounted on said top and formed with a dispensing opening in line with the path of said sifting openings and closing portion of said disc and having a depending finger engaging the slot of the disc, the outer end of said radial slot constituting means for limiting the rotary movement imparted by said outer closure through said finger to said disk in both directions to open and close said dispensing opening. 20

3. A dispensing top for a container having in combination, a stationary top adapted to be attached to a container and having a depressed circular pocket, a dispensing opening formed in and eccentric to said pocket, a disc seated in said pocket and rotatable therein and having sifting openings and a closing portion and a radially disposed slot extending toward the periphery of said disc, a gasket arranged on the face of said disc, and an outer closure rotatably mounted on said top and formed with a dispensing opening in line with the path of said sifting openings and closing portion of said disc and having a depending finger engaging the slot of the disc, the outer end of said radial slot constituting means for limiting the rotary movement imparted by said outer closure through said finger to said disk in both directions to open and close said dispensing opening. 25

4. A dispensing top for a container having in combination, a stationary top adapted to be attached to a container and having a depressed circular pocket, a dispensing opening formed in and eccentric to said pocket, a disc seated in said pocket and rotatable therein and having 30

sifting openings and a closing portion and a slot extending radially toward the periphery of said disc, an outer closure rotatably mounted on said top and formed with a dispensing opening in line with the path of said sifting openings and closing portion of said disc and having a depending finger engaging the slot of the disc, and an arcuate groove in said pocket for receiving the lower end of said finger to insure continuous driving engagement of said finger with 35 said disc. 40
